CLAIM

The ornamental design for a display screen with a graphic user interface, as shown and described.

DESCRIPTION

FIG. 1 is a front view of a first image in the sequence for a display screen with a graphic user interface showing an embodiment of our new design.

FIG. 2 is a front view of a second image thereof.

FIG. 3 is another front view of a first image of the first embodiment, shown with alternative unclaimed portions.

FIG. 4 is another front view of a second image of FIG. 3.

FIG. 5 is another front view of a first image of the first embodiment, shown with alternative unclaimed portions.

FIG. 6 is another front view of a second image of FIG. 5.

FIG. 7 is another front view of a first image of the first embodiment, shown with alternative unclaimed portions.

FIG. 8 is another front view of a second image of FIG. 7.

FIG. 9 is a front view of a display screen with a graphic user interface showing another embodiment of our new design; and,

FIG. 10 is a front view of an alternative configuration thereof in FIG. 9.

The broken line showings of the display screen, patterns, and characters are for the purpose of illustrating unclaimed portions of the display screen with a graphic user interface and form no part of the claimed design. The appearance of the transitional image sequentially transitions between the images shown in FIGS. 1-2, FIGS. 3-4, FIGS. 5-6, and FIGS. 7-8. The process or period in which one image transitions to another image forms no part of the claimed design.
